UNITED STATES PATENT OFFICE.

ROBERT C. MATHEWS, OF NEW YORK, N. Y., ASSIGNOR TO WESTERN ELECTRIC COMPANY, INCORPORATED, OF NEW YORK, N. Y., A CORPORATION OF NEW YORK.

SECRET SIGNALING.

Application filed June 30, 1923. Serial No. 648,648.

To all whom it may concern:

Be it known that I, ROBERT C. MATHEWS, a citizen of the United States of America, residing at New York city, in the county of

5 Bronx and State of New York, have invented certain new and useful Improvements in Secret Signaling, of which the following is a full, clear, concise, and exact description.

10 The present invention relates to the secret transmission of waves for any desired purpose, such as for signaling.

The invention is particularly applicable to the transmission and reception of waves, 15 the components of which extend over a considerable frequency range and have a characteristic frequency order as, for example, speech waves. The invention takes advantage of the fact that any material alteration 20 in the order of occurrence of the various frequency components of the wave makes it difficult to restore the wave to its characteristic form so that an unauthorized person who may intercept the wave being secretly 25 transmitted is unable to restore it to recognizable or understandable form.

An object of the invention is to secure a 30 high degree of secrecy in wave transmission with comparatively simple apparatus.

35 A further object is to enable secret radio communication to be effected with the expenditure of no more energy than is necessary for non-secret communication.

Briefly and specifically described, the invention comprises subdividing the waves to be transmitted as to their frequency components, into sub-bands of frequencies, and producing a phase or time shift in some of the sub-bands with respect to the others before transmission. In the specific embodiment of the invention to be described, this time shift is produced by the use of a storage device. The various sub-bands are then recombined and transmitted at their 45 own frequencies or they may first be shifted to a different frequency level and then be transmitted. Each of the sub-bands is preferably of such narrow frequency range as to be incapable of reproducing the speech 50 or other wave being sent, so that it is impossible to receive the signal by filtering out any one of the sub-bands from the others. At the receiving station employing the invention, the various sub-bands are separated by filtering, and such a time shift

is made in the individual sub-bands as is necessary to reproduce the speech or other waves.

The various features and objects of the invention will be more fully apparent from the following detailed description of the embodiment of the invention illustrated in the accompanying drawing. In the drawing, Fig. 1 shows schematically a transmitting station employing the invention; Fig. 2 shows a receiving station according to the invention for cooperating with the station of Fig. 1; and Fig. 3 shows a form of storage device suitable for use in making the time shifts in the transmitted and received sub-bands.

In the system of Fig. 1, speech currents, present in the circuit 2 as a result of talking into the transmitter 1, are impressed upon the three analyzing filters F_1 , F_2 , and F_3 . These filters are preferably band filters having their constants so proportioned as to transmit adjacent portions of the speech frequency band. In the arrangement shown, for example, the filter F_1 may transmit frequencies from 100 to 800 cycles per second. Filter F_2 may select the frequencies 800 to 1500 cycles and filter F_3 the frequencies 1500 to 2200, on the assumption that the frequencies 100 to 2200 are to be transmitted. A different number of filters than the three shown may be used, if desired, and the frequency range of each filter will depend upon the number of filters used. Each of these filters may be designed in accordance with the principles disclosed in the patent to Campbell 1,227,113, May 22, 1917.

The frequency components selectively transmitted by the several filters are impressed upon the respective time lag devices TL_1 , TL_2 , and TL_3 . These devices are arranged in a manner to be described presently so as to introduce a different time lag in the transmission of the several sub-bands selected by the analyzing filters. The sub-bands with their different time lags are then impressed in common upon the circuit 3 from which they are applied to the transmitting modulator M . A source 4 of carrier waves is also coupled with the modulator M , so that the impressed sub-bands modulate the carrier wave and the modulated waves are impressed upon the transmitting antenna TA . The modulator M is preferably of the balanced tube type shown

in the patent to Carson 1,343,306, June 15, 1920, and the carrier source may be an oscillator of the type shown in the Hartley Patent 1,356,763, October 26, 1920. This type of modulator has the property of suppressing transmission of the unmodulated carrier wave component so that only the two side bands resulting from the modulation of the carrier by the applied sub-bands are present in the output of the modulator M. The breadth of the frequency band transmitted may be reduced by tuning the antenna TA to one of the two side bands or in the case of relatively high radio frequencies where it would be impracticable to suppress one of the speech bands by tuning the antenna, the modulation system disclosed in the patent to Osborne 1,361,488, December 7, 1920, may be employed to secure single side band transmission.

The nature of the time lag devices will be understood from considering Fig. 3. The telephone W is driven forward at a constant speed in any suitable manner beneath the recording and listening coils R_1 , L_1 , etc. The components representing one of the sub-bands, for example, the components transmitted through the filter F_1 , are applied to the recording coil R_1 so that a magnetic record of these components is made on the wire W. As the wire travels forward, the recorded variations are brought underneath the listening coil L_1 and currents are set up in this coil corresponding to those in the coil R_1 which produced the record. These components induced in the coil L_1 pass into the outgoing circuit and are applied to the circuit 3 of Fig. 1.

It will be seen, therefore, that the currents impressed on the coil R_1 are, after a certain time lag, transmitted into the outgoing circuit by the coil L_1 . The time lag introduced into any sub-band is determined by the setting of the coils R_1 and L_1 along the line of travel of the wire W, on the assumption that the wire maintains a constant speed. The record produced in the wire by the coil R_1 is effaced by the erasing coil E_1 .

The same wire W may serve for introducing time lags into a plurality of the sub-bands. For example, the recording coil R_2 may be connected to the filter F_2 and the listening coil L_2 may be connected to the outgoing circuit 3. By providing a different spacing between the coils R_1 and L_1 from that between the coils R_2 and L_2 , different time lags may readily be introduced into the different sub-bands.

It is not necessary that a time lag device be employed for each of the sub-bands and it may be desirable to transmit one or certain of the sub-bands without introducing any time lag. This may readily be done by simply omitting the corresponding time

lag devices from the paths of the sub-bands in Fig. 1.

It will be understood that the actual delay introduced in any sub-band is not to be so great as to prevent carrying on a conversation at the ordinary rate. A very slight amount of delay in the various sub-bands is sufficient to destroy the intelligibility of the waves as a whole. The sub-band from filter F_1 , for example, may be transmitted with no time lag, the sub-band from filter F_2 may have a time lag of 0.01 of a second, for example, and the sub-band from the filter F_3 may have a time lag of 0.03 of a second, for example. To anyone picking up the transmitted wave on a simple detector, the received components would appear only as noise currents incapable of being understood. If the observer should attempt to receive the speech by filtering out a single one of the sub-bands, he would be defeated since the frequency components comprised in any sub-band are of too narrow range to reproduce intelligible speech.

The wave transmitted from the station of Fig. 1 may be received and made to reproduce intelligible speech by the circuit shown in Fig. 2. The wave is received on the antenna RA and detected at D where any suitable detector, such as a vacuum tube detector, may be employed. A source 4' of continuous waves of the carrier frequency is connected to the detector. The detected currents are impressed upon the circuit 5, to which are connected the filters F'_1 , F'_2 and F'_3 . These filters may be duplicates of the filters F_1 , F_2 and F_3 , respectively, employed at the transmitting station to analyze the speech currents. These filters at the receiver

serve to separate the sub-bands and apply them individually to the respective time lag devices TL'_1 , TL'_2 and TL'_3 . These time lag devices may be of the type shown in Fig. 3, the currents selected by one of the sub-band filters being applied to one of the recording coils and the outgoing circuit 6 being connected to a corresponding one of the listening coils. The telephone wire W is given such a speed and the recording and listening coils are so spaced as to restore the normal time or phase relations obtaining between the several sub-bands in normal speech. For example, with the time lags assumed to have been introduced into the sub-bands selected by the filters F_2 and F_3 of Fig. 1, the speech may be restored at the receiver by introducing a time lag in the sub-band from the filter F'_1 of .03 of a second, a time lag in the sub-band transmitted by the filter F'_2 of .01 of a second and no time lag in the other sub-band. The total delay introduced by the transmitting and receiving time lag devices in the transmitted message is then .03 of a second. The restored sub-bands are impressed together on the cir-

cuit 6 and from there through the repeating coil 7 to the receiver R.

In practice, amplification will need to be introduced at various points of the system, but for the sake of simplicity, no attempt has been made to indicate this in the drawing.

It will be seen to be a feature of the invention that the provisions for obtaining 10 secrecy are made entirely within the limits of the speech band and, therefore, they lie within the frequency limits of one of the side bands of the modulated wave, so that 15 secrecy of communication is obtained when only a single side band is transmitted between the two stations. By suppressing one 20 of the side bands and the unmodulated carrier component, applicant is enabled to save about 5% of the amount of energy transmitted, since it has been found that the energy 25 represented by a side band of a speech modulated wave represents only about 1/6 of the total energy of the entire modulated wave. This feature makes the invention particularly suited for long distance radio 30 transmission, such as transatlantic communication. However, the invention may be applied equally well to wire transmission, either to ordinary telephone transmission or to carrier telephone transmission, and the invention is therefore not to be construed as limited to any particular manner or type of transmission.

What is claimed is:

35 1. The method of secret transmission of waves, the frequency components of which comprise a considerable frequency range, which comprises dividing said waves into sub-bands of frequency components, producing relative time shifts in the sub-bands, and then transmitting all of the sub-bands over the same path.

40 2. The method of secret transmission of speech, comprising dividing the speech waves into sub-bands of frequency components, producing different relative time shifts in the different sub-bands, and transmitting the resultant sub-bands over the same path.

45 3. The method of secret transmission of speech comprising separating the frequency components of normal speech into sub-bands of frequency components, each sub-band by itself being incapable of reproducing intelligible speech, producing different relative time shifts in the separate sub-bands, and transmitting the resultant sub-bands over the same path.

50 4. The method of secret transmission of speech comprising separating the frequency components of speech into sub-bands of frequency components, producing different relative time shifts in the separate sub-bands while maintaining the original frequency order of the components within the fre-

quency limits of each sub-band, and transmitting the resultant sub-bands over the same path.

5. The method of secret transmission of speech comprising dividing the speech waves 70 into sub-bands of frequency components, producing different relative time shifts in the different sub-bands, producing a carrier wave, modulating said carrier wave by said relatively shifted sub-bands and transmitting the resulting modulated wave.

6. The method of secret transmission of speech comprising dividing the frequency components of normal speech into sub-bands of frequency components, each sub-band by 80 itself being incapable of producing intelligible speech, producing different relative time shifts in the separate sub-bands, modulating a carrier wave in accordance with the relatively shifted sub-bands, suppressing 85 transmission of one of the two side bands of the resulting modulated wave and the unmodulated carrier component and transmitting to a distance the remaining side band.

7. The method of receiving the sub-bands 90 transmitted according to the method of claim 1 comprising separating the respective sub-bands, producing relative time shifts in the separate sub-bands to restore their normal relations and impressing the restored 95 sub-bands upon a common receiver.

8. The method of receiving speech from the sub-bands transmitted according to the method defined in claim 2 comprising separating the sub-bands, producing different 100 relative time shifts in the separate sub-bands to restore their normal relations, and impressing the restored sub-bands upon a common receiver.

9. The method of receiving speech from the modulated wave transmitted by the method defined in claim 5, comprising demodulating the wave to reproduce the sub-bands of speech frequency range, separating 105 the sub-bands, producing different relative time shifts in the separate sub-bands to restore their normal relations, and impressing the restored sub-bands upon a receiver.

10. The method of receiving speech from the side band of the modulated wave transmitted by the method of claim 6, comprising combining said side band with a continuous wave of the carrier frequency in a demodulating circuit to reproduce sub-bands of speech frequency range, producing different 115 relative time shifts in the separate sub-bands to restore their normal relations, and impressing the restored sub-bands upon a receiver.

11. In a telephone system, means to produce speech currents, a plurality of filters, each arranged for selectively transmitting a different sub-band of the frequency components of the speech currents, means for transmitting the sub-bands over a common 130

path, and means to alter the time of transmission of some of the sub-bands relative to the others.

12. In a telephone system, a source of carrier waves, means to modulate the waves from said source in accordance with the sub-bands resulting from the transmitting arrangement of claim 11, means to suppress

from transmission, one of the two side bands of the resulting modulated waves and the unmodulated carrier wave component and means to transmit the remaining side band to a distance.

In witness whereof, I hereunto subscribe my name this 26th day of June A. D., 1923.

ROBERT C. MATHES.
